UNITED STATES PATENT OFFICE.

ALEXANDER CHRISTIE McARTHUR, OF GRAFTON, NEW SOUTH WALES, AUSTRALIA.

ADJUSTABLE CURTAIN-POLE BRACKET.

1,121,384.

Specification of Letters Patent. Patented Dec. 15, 1914.

Application filed December 18, 1911. Serial No. 667,031.

To all whom it may concern:

Be it known that I, ALEXANDER CHRISTIE McARTHUR, a subject of the Kingdom of Great Britain, and resident at Grafton, in the county of Clarence and State of New South Wales, Australia, medical practitioner, have invented a new and useful Device Entitled Adjustable Curtain-Pole Brackets, of which the following is a specification.

My invention relates to a hanging device for curtains whereby these articles can be kept clear of the wall and may be readily lowered for changing or other purposes.

According hereto poles for carrying curtains are supported in rings on brackets secured to the wall one on each side of the window.

Means are employed for retaining the brackets in any desired position.

The invention is illustrated in the accompanying drawings in which:

Figure 1 is a front plan of all the parts in position; Fig. 2 is a side elevation of bracket; Fig. 3 shows a front and side view of part 16; Fig. 4 is a front and side view of part 18; and Fig. 5 is a front and side view of 25.

All the drawings are one half actual size. Referring to Figs. 1 and 2, the bar 1 tapers from the upper end 10 to the lower end 9. A ring 2 is at the upper end of the bar 1, through which the pole 8 passes and by which it is held in position. The bifurcated extremity 3 from 9 to 11 consists of two branches each in the form of a double arc, the ends of which hit into and form hinges with 6 at 5.

The plates 4 have 3 holes 12, two above one below, by which each is secured to the wall near to and one each side of the window. Each plate 4 has two pairs of semicircular lugs 6, the lugs of each pair placed at one of the ends of the plate are separated by a space 7 into which the rounded ends of 3 fit and by means of pins riveted form the hinges 5.

1, 2, 3, of Figs. 1 and 2, are cast in one piece and, the plane of the ring 2 is at right angles to the plane of the bifurcation 3.

Fig. 2 shows one semicircular lug 13 on the back of the upper end of bar 1. 14 is an eyelet in 13 with edges rounded off smooth for the cord 15, Fig. 1.

1, 2, and 3 by means of the hinges 5 form 55 with plate 4 each bracket.

Fig. 3, shows front and side views re-

spectively of plate 16. It has two holes 20 by which it is secured to the wall, and in the middle, one semicircular lug 17 with an eyelet 21, with edges rounded off smooth 60 through which cord 15 passes.

Fig. 4, is a front and side view respectively of plate 18. It has three holes 19 by which it is secured to the wall, and two semicircular lugs 22, the upper placed vertically, the lower horizontally. Each lug 22 65 has an eyelet 23 with edges rounded off smooth for the passage of the cord 15.

Fig. 5, is a front and side view of a screw knob 25.

The device is worked as follows:—The plates 4 of brackets 1, 2, 3, 4, are secured to the wall one on each side of and near to the window at the required height from floor in such a way that the rings 2 will keep the 75 pole 8 horizontal. Plate 18, Figs. 1 and 2, is secured to the wall at 19 on the right side of window, the upper eyelet 23 of 22, Figs. 1 and 4, being opposite to the eyelet 14 of 13 Fig. 2 on the same side. Plate 16, Figs. 1 and 3, is secured to the wall at 20 on the left side of window, the eyelet 21 of 17 Figs. 1 and 3 being opposite to the eyelet 14 of 13 Fig. 2, on the same side. A cord 15 Fig. 1, of the required length has its free ends 80 threaded, the upper one through eyelet 23 of upper lug 22 on plate 18, Figs. 1 and 4, the lower one through eyelet 23 of lower lug 22 on plate 18, Figs. 1 and 4. The upper cord is carried across the top of the window, 85 threaded through eyelet 21 of 17 on plate 16, Figs. 1 and 3 on the left side, then threaded through eyelet 14 of 13 at the back of the upper end of bar 1 Figs. 1 and 2 on the same side and knotted. The lower cord on the 90 right side is threaded through eyelet 14 of 13 at the back of the upper end of bar 1, Figs. 1 and 2, on the same side and knotted. This leaves a long loop end free, on pulling 95 both cords at the one time the brackets 1, 2 and 3, with the pole 8 through the rings 2 can be raised or lowered. A knot is made 100 in the double cord of the loop end, at a place that will not interfere with the full lowering of the curtain-pole, and passed over the knob 25 Figs. 1 and 5 secured to the wall, which then holds the upraised bracket with pole. On releasing cord 15 from knob 25, 105 the brackets with the pole can be gradually lowered to within easy reach and the curtains readily affixed to the curtain rings on the pole. On releasing 15 from 25 the rings 110

2 of brackets 1, 2 and 3, with pole 8 describe an arc of a circle in a forward direction the hinges 5 acting as centers.

Pulleys of the lazy pattern may be substituted for plates 16 and 18.

I am aware that prior to my invention hinge-plates rings and eyelets for other devices have been used, but I am not aware that all the relative parts of my combination 10 have been used together for the purpose indicated.

I claim:

A curtain pole support comprising a pair of wall plates, each plate having a pair of 15 laterally extending semi-circular lugs at each end of the plate, the lugs of each pair being spaced apart, a pair of supporting arms, each of said supporting arms being

provided with a fork at one end, the arms of the fork being arranged to enter between 20 the lugs at opposite ends of the plate and being pivotally secured to the lugs, the lugs of each pair serving as opposed brace members, the opposite end of each of the arms being provided with an integral ring, the 25 ring on one arm being alined with the ring on the other arm to receive a curtain pole, and means for simultaneously moving said supporting arms on their pivots.

Dated this fourth day of November, A. D. 30 1911.

ALEXANDER CHRISTIE MCARTHUR.
